UNITED STATES PATENT OFFICE.

JOSEPH E. FOWLER, OF WORCESTER, MASSACHUSETTS.

BURNER.

Application filed December 12, 1921. Serial No. 521,699.

To all whom it may concern:

Be it known that I, JOSEPH E. FOWLER, a citizen of the United States, residing at Worcester, in the county of Worcester and State of Massachusetts, have invented new and useful Improvements in Burners, of which the following is a specification.

This invention relates to a burner, the general object of the invention being to so 10 arrange the parts that the fuel will be thoroughly vaporized thus insuring a perfect combustion with intense heat.

Another object of the invention is to provide a combined deflector and protector at 15 the top of the burner for deflecting the flame outwardly and at the same time preventing material from dropping into the burner.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is an elevation of the invention.

Figure 2 is a longitudinal sectional view.

Figure 3 is a section on line 3—3 of Figure 1.

As shown in these views the burner includes the base 1, the top 2 and the spaced 35 perforated cylinders 3 which are supported on the base and the inner one of which is connected with the top. The parts are held together by the bolt 4 which has its head en-

40 gaging the top and its screw threaded end the base. The base is formed with an annular trough 5, the outer circumference of which supports the outer cylinder, and a ring 6 of asbestos or the like is suitably supported in 45 said trough and acts as the initial heating means. Passages 7 are formed in the base and these passages radiate from the central opening 8 to the periphery of the base so as to lead the oil coming from the supply pipe

50 9, which is connected with the opening 8, to the trough. The outer cylinder is provided with an opening 10 through which a match or other igniter can be passed to ignite the ring 6 and a hole 11 is formed in the outer 55 wall of the trough and said cylinder and acts as a gage for the fuel entering the trough.

The base 2 is of cup-shape, as shown, and extends above the top of the inner cylinder, the outer wall of this extended part being slightly curved to deflect the flames outwardly. A combined deflector and protector 12 is removably seated in the top 2 and this member is provided with outwardly flaring walls 13 which form continuations of the curved wall of the top and extend over 65 the upper ends of the cylinders. This member acts to prevent liquids, which may boil over from a utensil placed over the boiler, from entering the space between the cylinders and extinguishing the flame and also 70 acts as a deflector for the flame so as to heat all portions of the stove or other device in which it is placed. The member 12 is provided with a handle 14 so that it can be removed and replaced as desired. 75

A valve casing 15 is connected with the pipe 9 and with a supply 16 and the passage through the casing is controlled by a needle valve 17. A stop 18 is associated with the needle valve for limiting the movement 80 thereof.

When the burner is to be used the needle valve is opened to permit a supply of fuel to flow up the pipe 9, through the passages 7 into the trough so as to saturate the ring or 85 wick 6. The hole 11 acts as a gage for limiting the amount of fuel in the trough. A match or other igniter is then passed through the opening 10 to ignite the fuel on the wick and the combustion of this fuel will act 90 to heat the base and its associated parts and when these parts are sufficiently heated the fuel passing through the passages 7 will be vaporized and this vapor will burn with a blue flame at the cylinders and the flame will 95 be directed outwardly by the walls of the top 2 and the member 12.

If the device is placed in a position where it is impossible to ignite the wick through opening 10 the member 12 may be lifted off 100 and the wick ignited through the space between the cylinder.

It is thought from the foregoing description that the advantages and novel features of my invention will be readily apparent. 105

I desire it to be understood that I may make changes in the construction and in the combination and arrangement of the several parts, provided that such changes fall within the scope of the appended claims. 110

What I claim is:—

1. A burner of the class described com-

prising a base, a cup-shaped top and a pair of spaced perforated cylinders, said base having fuel passages therein communicating with the space between the cylinders, means for feeding fuel to said passages and a combined deflector and protector having a part seated in the top.

2. A burner of the class described comprising a base, perforated cylinders supported thereby and spaced apart, a trough

connected with the base and forming the bottom of the space between the cylinders, said base having passages therein communicating with the trough, means for feeding fuel to said passages, a wick in said trough, a gage opening in said trough and an opening in the outer cylinder for introducing a match to light the wick.

In testimony whereof I affix my signature.

JOSEPH E. FOWLER,
